UNITED STATES PATENT OFFICE.

JOSEPH FAVIL BIEHN, OF CHICAGO, ILLINOIS, ASSIGNOR TO THE ABBOTT LABORATORIES, OF CHICAGO, ILLINOIS, A CORPORATION OF ILLINOIS.

CLOSURE FOR HYPODERMIC-SOLUTION CONTAINERS.

1,413,703.

Specification of Letters Patent. Patented Apr. 25, 1922.

Application filed December 7, 1918. Serial No. 265,680.

To all whom it may concern:

Be it known that I, JOSEPH FAVIL BIEHN, a citizen of the United States, residing at Chicago, in the county of Cook and State of Illinois, have invented certain new and useful Improvements in Closures for Hypodermic-Solution Containers, of which the following is a specification.

My invention relates to improvements in 10 closures for hypodermic solution containers, and particularly relates to a closure which is so organized that a hypodermic needle may be forcibly thrust through the closure into the container for the purpose of with- 15 drawing a charge of the solution.

The arrangement is such that after the needle has been withdrawn from the container, the closure will automatically seal itself to prevent admission of air or foreign 20 matter, while at the same time preventing egress of the hypodermic fluid.

The object of the invention is to provide a simple, economical, efficient, and practical closure of the type referred to.

25 In the drawings, which illustrate a preferred embodiment of my invention—

Fig. 1 is a vertical section through a container equipped with my improved closure;

Fig. 2 is a plan view of the container 30 shown in Fig. 1; and Fig. 3 is a view showing the manner in which a charge of the solution is withdrawn from the container by means of the usual hypodermic needle.

Referring to the drawings, which are considerably larger than actual size so as to show the mechanical arrangement more distinctly, 10 represents a phial in which the solution for hypodermic purposes is put up and stored or marketed. Such phial which, 40 for obvious reasons, is usually made of glass, has a somewhat reduced neck portion 11, the outer end thereof having an annular enlargement 12 surrounding the mouth of the phial, thereby providing a circular rim or shoulder 45 der 13.

The sealing of the phial is effected by means of a stopper or closure 14 constructed of a suitable grade of soft vulcanized rubber. The said rubber member 14 has a cylindrical portion which fits snugly within the mouth and neck of the phial 10, and also is furnished with an outer projecting flange 15 which overlies a lip 16 of the phial. The flange 15 is forced into tight sealing engagement with the surface of the lip 16 of the

phial by means of a permanently applied thimble member 17, the bottom edge of which is spun or crimped around and below the shoulder 13, as shown at 18.

In order to permit the insertion of the 60 hypodermic needle to withdraw the solution, the rubber closure 14 is formed with a central opening 19, the top of the thimble member 17 being also correspondingly apertured, as indicated at 20. The opening 19 in the 65 outer end of the closure 14 is made co-axial with a somewhat similar opening 21 on the inside of the closure, said two cavities 19 and 21 being separated by a comparatively thin diaphragm 22 formed as an integral 70 part of the rubber closure 14. The thickness of the diaphragm 22 is such that the needle 23 of a hypodermic spring 24 may readily be thrust into the phial, as indicated in Fig. 3, for the purpose of withdrawing 75 a portion of the hypodermic solution 25. When the needle is withdrawn after filling the syringe, the hole in the soft rubber diaphragm 22 closes up automatically and thus insures that the remaining portion of the 80 contents of the phial will not escape, evaporate or become contaminated by exterior agencies.

In practice, I prefer to make the cylindrical portion of the closure 14 slightly greater 85 in diameter than the interior diameter of the neck of the phial so that the diaphragm 22 will be under a slight compression, thereby enhancing the natural tendency of the rubber to close up and seal the aperture or 90 apertures made therein by the insertion of the hypodermic needle.

In order to prevent foreign matter from gaining access to the top of the diaphragm and thus contaminating the point of the needle, I prefer to cover the top of the closure with a thin metal thimble shaped cap 26, which is a sufficiently good fit on the inner permanent thimble member 17 to prevent its coming off or becoming lost, while at the 95 same time the fit is loose enough to permit of its being readily removed when it is desired to withdraw a portion of the solution.

The scope of the invention should be determined by reference to the appended claims 105 rather than by reference to the mechanical details herein described.

I claim—

1. In combination, a container for hypodermic solutions provided with a neck and 110

- 2
- mouth thereto, a rubber sealing element fitting within the neck of said container and having a flange overlying the lip of the mouth thereof, permanently applied metallic 5 means for forcing said flange into tight fitting engagement with said lip, the inner and outer ends of said sealing element being each formed with a recess, and a sealing diaphragm formed as an integral part of said 10 rubber element constituting a partition between said recesses, and being readily perforable by the needle of a hypodermic syringe.
2. In combination, a container for hypodermic solutions provided with a neck enlargement constituting a shoulder, a rubber stopper snugly fitting within said neck and having an outer flange, an annular metallic member overlying said flange for holding 15 said flange in tight fitting sealing engagement with the lip of the mouth of said neck and having its lower edge formed to embrace said shoulder, said stopper being provided with an inner and an outer axially 20 extending recess, and a diaphragm constituting an integral part of said stopper and the wall between said recesses and capable of being readily pierced by the needle of a hypodermic syringe. 25
3. In combination, a container for hypodermic solutions provided with a neck enlargement constituting a shoulder, a rubber stopper fitting within said neck and compressed thereby, an annular flange formed on said stopper overlying the rim of said neck, 30 an annular metallic member overlying said flange and firmly pressing the same upon said rim, the lower edge of said member being crimped to permanently interlock with said shoulder, said stopper being provided 35 with an inner and an outer axially extending recess, a diaphragm constituting an integral part of said stopper, said diaphragm forming a closed partition between said recesses and extending transversely within the 40 neck of said container, and a cap fitting over said member. 45

JOSEPH FAVIL BIEHN.
